UNITED STATES PATENT OFFICE.

WALTER S. RUSSELL, OF LOS ANGELES, CALIFORNIA.

MATERIAL-HANDLING DEVICE.

Application filed January 4, 1926. Serial No. 79,062.

This invention has to do generally with material handling devices, and is especially well adapted for embodiment in devices for handling sizable rocks, though in no way limited to such specific embodiment. In order that the nature and objects of the invention may be clearly pointed out, I have chosen to describe its embodiment in a device of this character, and from this description, those skilled in the art will readily understand how the invention may be embodied in devices having somewhat different physical characteristics, especially when materials other than sizeable rocks are to be handled.

It will, therefore, be understood that the following description of the particular structure illustrated is not to be considered as in any way limitative on the invention considered in its broader aspects. For instance, I have shown one form of the device mounted on trucks so it may be moved through a quarry cut as the quarrying operations progress; but it will be understood that it is not essential to the invention that the device in which it is incorporated be of the mobile type.

In quarrying large rocks, great difficulty has been had in loading cars economically and expeditiously. This condition arises mainly as a consequence of the necessity for screening out smaller particles before the car is loaded and from the destructive effect of "chuting" large rocks against the sides of the cars. Since it is essential that the finer material be screened out, the use of a steam shovel to load the cars directly is precluded, and consequently it is common practice to run a line of dump cars from the cut to a central handling plant where the screening and loading are accomplished. This double handling is, of course, an expensive procedure, and after the screening is finished, there still exists the necessity for chuting the larger rocks into the car. The consequent battering of the car sides is most destructive and it is not at all unusual to find a car body wrecked after one or two loadings.

I overcome these objectionable features by providing a platform, preferably mounted on track guided trucks, upon which the material is directly dumped from the steam shovel, the platform being moved forwardly

into the cut as the steam shovel advances. On the platform is a normally horizontal chute, preferably in the form of a heavy screen. For instance, it may include a bottom made up of a plurality of heavy grizzly bars. The finer particles pass through the grating which is thereupon inclined to form a chute whereby the larger rocks are directed into the open side of a bucket by which delivery is made to the cars. As will hereinafter be made apparent, this bucket may move to a dumping position over the cars simultaneously with the inclination of the platform chute, or it may be moved independently thereof. In the first instance, the chute and bucket may be hung upon a common horizontal pivotal axis; while in the second instance the bucket may move independently and vertically.

In both instances, dumping from the bucket is accomplished by opening bottom gates, and since the buckets, in dumping position, may be relatively close to the car bottom, when the gates are opened the rocks have but little fall, and therefore, the shock of their impact with the car bottom is so slight that no appreciable damage is done. In certain instances, it is even possible to lower the bucket until it engages or very nearly engages the car bottom. By then releasing the gate holding means and subsequently raising the bucket, the rocks are, in effect, merely laid upon the car bottom. As the height of the rock deposit in the car increases, the bucket may be lowered to a lesser degree before it is dumped.

Other objects and novel features of the invention will be made apparent in the following detailed description wherein reference will be made to the accompanying drawings, in which:

Fig. 1 is an end elevation of one embodiment of the invention wherein the loading chute and bucket are adapted to move as one about a horizontal axis. The chute and bucket are shown in charge-receiving position;

Fig. 2 is a view similar to Fig. 1 but showing the chute and bucket in discharging position;

Fig. 3 is a plan view of Fig. 2;

Fig. 3^a is an enlarged fragmentary section on line 3^a—3^a of Fig. 3;

Fig. 4 is a fragmentary elevation of the device as viewed from the right of Fig. 3;

Fig. 5 is a section on line 5—5 of Fig. 4;

Fig. 6 is an enlarged detail, partly in elevation and partly in broken away section, of the bucket and mounting therefor;

5 Fig. 7 is a fragmentary section on line 7—7 of Fig. 6;

Fig. 8 is a fragmentary section on line 8—8 of Fig. 7;

10 Fig. 9 is a fragmentary section on line 9—9 of Fig. 6;

Fig. 10 shows a variational form of the device;

15 Fig. 10^a is a conventional showing of a hoisting mechanism for operating the device shown in Fig. 10;

Fig. 11 is a fragmentary section on line 11—11 of Fig. 10; and

Fig. 12 is a view of Fig. 10 as viewed from the right thereof.

20 I will first describe that form of handling device which is of the mobile type, and in which the loading platform or chute and bucket move as one to and from discharge position; though it is to be particularly noted that the invention, considered in its broader aspects, is not limited to a device having these particular characteristics. Numeral 10 designates generally a movable platform having wheels 11 adapted to be 25 guided by rails 12 which are laid in advance of the platform as the steam shovel (not shown) advances through the cut being made through the quarry. Platform 10 has a deck 13 and an elevated supporting structure 14, the latter being held in vertical spaced relation with deck 13 by posts 15, suitable bracing 16 being provided. Rising from structure 14 is a super-structure generally indicated at 17 and consisting of 30 spaced vertical posts 18, cross beams 19 and 19^a, inclined braces 20 and horizontally extending cross braces 21 and 22, braces 22 extending forwardly beyond posts 18 as clearly shown in Figs. 1, and 3. A crown block or 35 sheave 23 is mounted on header blocks 23^a which are supported by upper beams 19^a approximately midway between posts 18.

40 Supporting structure 14 includes longitudinally extending sills 24 and lateral beams 25, said beams overhanging one side of the car as at 26. It is on these overhanging portions 26 that posts 18 are supported. Diagonal tension rods 27 tie posts 18 to the supporting structure and diagonal tension rods 45 tie the overhanging portions of beams 22 to the posts, attachment between rods 28 and beams 22 being made by pins 29, these pins projecting from the sides of the beams 55 in a manner to form limit stops for the bucket, as will be hereinafter described.

50 A loading chute is indicated generally at 30, this chute being pivoted on a horizontal axis 31 which is supported by beams 25 in a manner to be described later, but the chute is normally maintained in a horizontal

position during load receiving operations. It lies within the scope of my invention to fashion this chute in any suitable manner, and it may or may not have the characteristics of a grizzly or grating. Preferably, 70 however, it has these characteristics so that screening may be accomplished during the loading operation. As a preferred type of construction, chute 30 is made up of spaced horizontal channels 31^a and connecting H-beams 32. Also connecting channels 31 are H-bars 33 and Z-bars 34 upon which rest the spaced grizzly bars 35. Bars 35 are held in pre-determined spaced relation by tubular spacers 36 which are carried around bars 37, the latter being removably held to channels 31 by nuts 38. The forward ends of bars 35 may be notched as at 39 (Fig. 6) so the upper edges of said bars 35 lie flush with plate 40 which rests and extends between H-beams 32^a, 32^b, to form the bottom of bucket B when the latter is in load-receiving position and one side of said bucket when in load delivering position. The ends 41 of the bars extend beneath the flange of beam 32^a, but when it is desired to replace the grizzly bars to change the mesh of the grating or for purposes of repair, the grizzly bars may be readily removed by first withdrawing rods 37 and then inclining the bars so ends 41 may be withdrawn from beneath the H-beam flange. Plates 42 extend upwardly from channels 31 to form the sides of the chute, while plates 43, braced by angle irons 44, extend upwardly from said channels to form the sides of 100 buckets B; it being noted that by this construction the loading chute and bucket are rigidly interconnected by channels 31 and will, therefore, move as one when the device is being operated.

105 The chute and bucket are mounted for movement about the common horizontal pivotal axis provided by shaft 45 which extends between boxes 46 on overhanging portions 26 of beams 25. This shaft extends through plates 43 and channels 31 and is preferably of square cross-section except at its ends 47 where it extends outwardly beyond channels 31. The square portions of the shaft pass through complementarily shaped openings 115 45^a (Fig. 9.) in channels 31 and plates 43 so the shaft and bucket-end-chute assembly are held against relative rotation. Extensions 47 are of circular cross-section and take the rigidly connected sheave 48 and have bearing in boxes 46. Connection between plate 40 and shaft 45 is preferably made through angle irons 49.

120 The side of the bucket opposite plate 40 is closed by plate 50; the outer ends of said plate 50 and of plate 40 defining discharge mouth 51. The bucket is open at the side opposite mouth 51 so when the chute and bucket are inclined, material from the chute slides into the bucket and against gates 130

which are pivotally movable to open and close mouth 51.

Gates 52 are arcuate plates, one of said plates having hinge connections 53 with a hinge pin 54 which extends between the ends of channels 31, and the other plate having hinge connections 55 with a hinge pin 56 extending between plates 43 at the opposite side of mouth 51. Plates 52 have angle iron reinforcements 57, the outermost angle irons 57^a carrying outwardly projecting studs 58. When in closed position, plates 52 engage the forward edges of plates 43 and thereby close mouth 51.

Various means may be employed for controlling the movement of gates 52, but I prefer to employ the travelling block tackle and mechanism shown in the drawings, special reference being made to Figs. 6 and 7. The same type of control mechanism is used at each side of the bucket, and I will, therefore, describe only that at one side. Links 59 pivotally connect studs 58 and shaft 60 upon which shaft is mounted travelling block 61. One end of dump-control cable 62 is anchored to shaft 60 at 63, the cable being trained about sheave 64, then about block 61 and back to sheave 65. Sheaves 64 and 65 are carried on shaft 66 which is supported between plate 43 and yoke 67, the latter being secured to plate 43 by rivets 68 and definitely spaced from said plate by bolts 69 and tubular spacers 70.

Cable 62 runs from sheave 65 to sheave 48, it being noted that since sheave 48 is on the pivotal axis of the bucket, pivotal movement of said bucket in no way effects the tension of the cable. From sheave 48, cable 62 is trained over cross sheaves 71 and 72 on shafts 73 and 74, respectively. The last named shafts are supported from structure 14 in any suitable way (see Fig. 1). Cable 62 runs from sheave 72 to drum 75 of hoist H which is here shown conventionally since it may be of any suitable type. A cable 62^a leads from drum 75 to the dump control mechanism on the opposite side of the bucket, in a manner similar to that described in connection with cable 62.

Assuming that the bucket is in the inclined position of Fig. 2, and gates 52 are closed, it will be seen that material in the bucket as well as the weight of the gates tends to swing said gates open to dotted line position. This opening movement is, however, resisted by holding cable 62 from movement so block 61 and hence links 59 and gates 52 are held from dropping. The cable is thus releasably held by application of usual brakes (conventionally shown at 75^b) to brake drum 75^a.

By releasing said drum 75 from the effect of its brake, gates 52 are left free to gravitate to dotted line position, links 59 spreading angularly and blocks 61 lowering in the

manner clearly shown. The rapidity of this movement may be controlled, of course, by proper manipulation of the drum brake. When gates 52 are thus opened, material within the bucket is discharged into railroad car C, the degree of inclination of the chute 31 existing at the time of dumping and the extent of gate opening depending upon the particular situation existing during the operation. The size of the load, the relative size of the rocks making up the load, the height of the bucket above the car bottom or material already disposed upon said bottom are some of the controlling factors in determining the relative time and extent of gate opening. Of course, in any event, the chute is always inclined sufficiently beyond the angle of repose of the particular material being handled, to insure that said material will slide from the chute into the bucket so it may be deposited in car C when the gates are opened. In some situations it may be desirable to start opening the bucket while the chute is still mounted upwardly; and in other situations, it is desirable that the bucket be not fully opened until the chute starts its movement back to horizontal position. Conditions under which such relative movements are advisable will be well understood by those skilled in the art.

When the bucket is to be closed, cables 62 and 62^a are taken up by rotation of drum 75 through the medium of the conventionally illustrated engine designated at E; this taking up of the cables moving blocks 61 towards sheaves 64 and 65, thereby reducing the angle between links 59 and hence drawing the free ends of gates 52 together to closing mouth 51. This closing movement of the gates may occur with either the bucket at rest or during its pivotal movement in one direction or the other.

I will now describe the preferred method of inclining the bucket and chute and for returning them to normal or horizontal position. While any suitable tilting and return mechanism may be employed, or while I may even depend upon gravity for causing pivotal movement in either one direction or the other, the preferred method of pivotally moving the chute and bucket is that shown in the drawings. At this time it may be well to note that it is desirable and usually necessary (in the absence of other anchoring means) to provide ballast boxes S at that side of the car which is remote from the bucket; the ballast boxes being loaded down with sufficient weight to insure that the loading car is not over balanced at any stage of the operation.

For moving the chute and bucket to discharge position, I provide chute 30 with a bridle 77, the free ends of which are pivotally connected with channels 31 at 78, while its closed end carries sheave 79. A

hoisting cable 80 is anchored to bridle 77 at 81, and is trained around sheave 82 which is pivotally connected to the shaft 23^b of the crown block 23 by links 83. From the 5 sheave 82 cable 83 is brought around sheave 79 and then carried over crown block 23 from whence it passes over sheaves 84 and 85 to drum 86 of hoist H, said drum being provided with the usual brake drum 87 and 10 braking mechanism of usual type conventionally illustrated at 87^a.

Sheave 84 is supported on hangers 88 which depend from beam 19^a; while sheave 85 is mounted on a diagonal piece 89 which 15 extends from beam 22 to beam 21 of the super-structure.

While separate hoist and return cables may be used for pivotally moving the loading chute in opposite directions, and while 20 these cables may be operated by independent mechanisms, I prefer to utilize a single cable and drum for this purpose. However, I will refer to that portion of the single cable which is operated to lower the chute, as a 25 "return cable." Thus, after cable 80 is coiled about drum 86, it is taken off at 91 and carried over horizontally arranged sheave 92, the latter being supported on deck 13 as clearly shown in Fig. 2.

30 Portion or length 91 will hereinafter be referred to as a return cable so it may be more readily distinguished from that portion of the cable which is operated to raise the chute, though, as mentioned above, length 35 91 is here shown as a continuation of cable 80. From sheave 92 cable 91 passes over sheave 93 which is mounted on brace 94^a of supporting structure 14. A sheave 94 is pivotally connected to shaft 95 of sheave 93 40 by links 96; while a sheave 97 is secured to the under side of chute 30, approximately midway between channels 31^a, by links 98. Cable 91 passes from sheave 93 over sheaves 97 and 94, its free end being anchored to 45 links 98 at 99. Where the hoisting and return cables are operated from a common drum, it is necessary, of course, that the blocks of the tackle on the hoisting and return side be of such ratio that they pay out and take up equally when the common drum 50 is revolved in either direction.

It will be understood without further discussion how rotation of drum 86 in opposite direction will positively raise and lower the chute and bucket, the movement of said chute and bucket being constantly under the control of the operator irrespective of the weight of the load on the chute or in the bucket.

55 In order that the strain may be taken off of the tackle when the bucket is in the upright, discharging position of Fig. 2, I prefer to provide arms 100 on the sides of bucket 13, attachment of these arms being conveniently made by applying them to

bracket or yokes 67 and securing them in position by means of bolts 69. Arms 100 are adapted to engage stop pins 29 to limit the pivotal movement of the chute and bucket in one direction, and I may provide said arms 70 with hook ends 101 so when pins 29 are engaged, the horizontal overhanging portions of the hook ends engage the pins 29 so the down-bearing load of the bucket will be taken, in part, by these pins and transmitted 75 to the super-structure, rather than being imposed solely on the return or holding tackle and shaft 45.

In order to carry away and properly dispose of the screenings which pass between 80 grizzly bars 35, I may dispose a belt conveyor 102 beneath said bars. An inclined conveyor 103 is adapted to take the material from conveyor 102 and deliver it outside the car. Conveyors 102 and 103 may be driven 85 from any suitable mechanism, for instance, power shaft 104 may be operatively connected at 105 and 106 to conveyors 102 and 103 respectively, shaft 104, in turn, being driven directly from any suitable independent prime mover (not shown) or operatively connected to the power plant of the hoisting mechanism at 107.

I will now describe the variational type of loading device shown in Figs. 10, 11 and 95 12; wherein the bucket and chute are independently movable; the chute being adapted to be moved pivotally about a horizontal axis and the bucket being adapted to be reciprocated vertically. In Figs. 10 and 12 I 100 have shown a tower frame consisting of inclined uprights 110, cross braces 111 and headers 112, 113, 114, and 115. Loading platform P rests upon cross pieces 116 which are secured to uprights 110, and extends as 105 at 117 partly into the tower. Dropped from the end of extension 117 is an apron 118 which is supported at its lower end by member 119 on braces 120 extending between two of the uprights 110. During certain stages 110 of the operation, apron 118 forms a closure for the otherwise open side of bucket B'.

Chute 121 may be fashioned in much the same manner as chute 30, except that it is movable independently of bucket B'. Chute 115 121 may have a grating or grizzly bar bottom 122, as indicated in Fig. 12, and is pivoted at 123 on block 124 at the end of extensions 117. Normally, chute 121 is in the horizontal position indicated by dotted lines, its rearward end resting on block 125 which extends upwardly from platform P. The chute may be loaded directly from a steam shovel or from a second chute 126 supported above platform P by structure 127. The forward end of chute 121 opens into bucket B' through open side 128 thereof, so when the chute is raised to the full line position shown in Fig. 10, material within the chute will slide into said bucket, the bucket ordinarily, 125 130

though not necessarily, being in the raised position indicated by full lines in Fig. 10 when the material is thus delivered to it.

While it lies within the scope of my invention to move chute 121 pivotally from horizontal to inclined position with any suitable mechanism, I prefer to utilize the tackle here illustrated and including a bridle 130 pivotally secured to the chute at 131 and carrying link 132 which supports sheave 133. A grizzly-hoist cable 134 is anchored to link 132 at 135, and is trained around crown sheave 136, around sheave 133, and over crown sheaves 137 and 138 to sheave 139 at the base of the tower. From sheave 139 cable 134 leads to drum 140 of the hoisting engine conventionally illustrated at H'. 141 designates the power shaft of this engine, which shaft is adapted selectively to drive drums 142 and 143, as well as drum 140. Suitable clutches 144, which are shown conventionally since they are well known to those skilled in the art, provide means whereby the drums may be driven simultaneously or independently, and each of the drums has a usual brake band 145 to which ordinary braking mechanism, indicated at 145^a, may be applied in the usual manner for retarding or stopping rotation of the drums.

Secured to braces 111 of the tower frame are vertical posts 146 which serve to guide bucket B' throughout all periods of its vertical movement. Bucket B' is substantially rectangular in horizontal cross section, being open at one side 128 for the reception of material from chute 121, and the nose 147 of the chute is preferably adapted to extend through this open side in order to prevent spillage of material between the chute and bucket. The bucket may also have an outwardly turned lip 148 which is disposed at side 128 below nose 147 and extends into proximity with apron 118 to prevent material within the bucket from spilling out the open side of the bucket and downwardly along apron 118 as the bucket is lowered. Vertically spaced channels 149 are secured to both sides of bucket B' and extend therebeyond into facial engagement with posts 146, the channels being adapted to engage said posts slidably as the bucket is reciprocated vertically and thus serving to hold the bucket from swinging to right or left, as viewed in Fig. 12. Angle irons 150 are secured to the inner faces of channels 149, and slidably engage the opposed inner faces of posts 146 as the bucket is reciprocated, thus serving to hold the bucket from swinging to left or right as viewed in Fig. 10.

Gates 151 are hinged at 152 to the side plates of the bucket, and when closed, are inclined as shown in Fig. 10 to form a hopper bottom for the bucket.

The bucket is lowered and raised by

cable 153 which is secured at 154 to a bridle 155 extending upwardly from bucket B. This bridle also carries a sheave 156. Cable 153 runs from bridle 155 over crown block 157, thence around sheave 156, and then over 70 crown sheave 158 to drum 142.

Pivottally connected to the lower ends of gates 151 are links 159, the opposite ends of said links being pivotally connected at 160 to the shaft 161 carrying a sheave 162. It will 75 be understood the gate actuating mechanism is duplicated at the opposite side of the bucket, but since the two mechanisms and tackle for controlling the same are identical, I will describe but one in detail. Dump 80 control cable 163 is anchored at 164 on a yoke 165 carried by shaft 161, and passes thence over crown sheave 166, around sheave 162 and over crown sheave 167 to drum 143. Cable 163', from the opposite gate actuating 85 mechanism, is trained in the same manner over corresponding sheaves and passes to drum 143.

After chute 121 has been inclined to empty its contents into bucket B', cables 90 153, 163 and 163' are paid out equally by coincident rotation of drums 142 and 143, tension being maintained on cables 163, 163', in order to maintain gates 151 in closed position. As soon as the bucket is lowered to 95 dumping position, and this position will be determined by the size of the load, height of the floor of railroad car R, etc., drum 143 is rotated independently of drum 142 in a manner to pay out cables 163 and 163'. This 100 results in allowing the load within bucket B', as well as the weight of gates 151, to swing the gates downwardly, and thereby open the lower end of the bucket so the load may be deposited in car R.

When the gates are to be closed, drum 143 is rotated to take up cables 163 and 163' which raises sheave 162 and links 159 in a manner to swing gates 151 inwardly and back to the full line position of Fig. 10. Assuming that the bucket has not been raised during the closing movement of the gates, as soon as the gates are closed and the bucket is raised by rotation of drum 142, coincident and equal rotation of drum 143 is necessary 115 in order that slack may not develop in the dump control cables and thereby allow the gates to reopen unintentionally. Of course, by rotating drum 143 faster than drum 142, the gates may be closed during the ascension 120 of the bucket; or, if desired, the bucket may be raised to load-receiving position before the gates are closed, but in this latter event, slack will develop in the dump control cables unless drum 145 is rotated coincidentally 125 and equally. It then requires independent taking-up of cables 163, 163' to close the gates.

It will be understood the drawings and description are to be considered merely as 130

illustrative of and not restrictive on the broader claims appended hereto, for various changes in design, structure and arrangement may be made without departing 5 from the spirit and scope of said claims.

I claim:

1. In a device of the character described, a dump bucket having a downwardly opening discharge mouth, a pair of closure gates hingedly connected to the bucket adjacent the mouth, and releasable means adapted to hold said gates closed; said means including a pair of links pivotally connected to one another at their upper ends and pivotally connected at their lower ends, one to each of said gates, a travelling sheave at the pivotal connection between links, a sheave, stationarily mounted, except for rotation, on the bucket, a cable trained over said sheaves, and means for operating said cable to vary the distance between said sheaves and hold them at adjusted position thereby to vary the angular disposition of the links and hold them in adjusted relative angular position, respectively.

2. In a device of the character described, a supporting frame, a dump bucket open at one side, a loading chute rigid with said bucket and opening into the bucket at said open side, said bucket and chute being mounted on the frame for pivotal movement about a horizontal axis and the chute being normally supported in horizontal position to receive its load, means for inclining the chute to cause it to deliver its load to the bucket through said open side; said bucket having a discharge mouth which opens downwardly when the chute is so inclined, downwardly opening gates for the discharge mouth, and releasable means adapted to hold said gates closed.

3. In a device of the character described, a supporting frame, a dump bucket open at one side, a loading chute rigid with said bucket and opening into the bucket at said open side, said bucket and chute being mounted on the frame for pivotal movement about a horizontal axis and the chute being normally supported in horizontal position to receive its load, means for inclining the chute to cause it to deliver its load to the bucket through said open side, means on the frame and bucket adapted to coact to limit the degree of inclination of the chute; said bucket having a discharge mouth which opens downwardly when the chute is so inclined, downwardly opening gates for the discharge mouth, and releasable means adapted to hold said gates closed.

4. In a device of the character described, a supporting frame, a dump bucket open at one side, a loading chute rigid with said bucket and opening into the bucket at said open side, a screen bottom in said chute, said bucket and chute being mounted on the

frame for pivotal movement about a horizontal axis and the chute being normally supported in horizontal position to receive its load, means for inclining the chute to cause it to deliver its load to the bucket 70 through said open side; said bucket having a discharge mouth which opens downwardly when the chute is so inclined, downwardly opening gates for the discharge mouth, and releasable means adapted to hold said gates 75 closed.

5. In a device of the character described, a supporting frame, a dump bucket associated with the frame, a pair of closure gates hingedly connected to the bucket, means for selectively moving said gates hingedly and holding them against movement hingedly; said means including a pair of links pivotally connected to one another at one end and pivotally connected at their other ends, one to each of said gates, a sheave connected to the links at a point spaced from their connection with the gates, a second sheave associated with the first sheave, said sheaves being capable of relative bodily movement, a cable trained over the sheaves, and means for operating said cable to move the sheaves bodily toward and away from each other and hold them at positions to which they have been moved thereby to vary the angular disposition of the links and hold them in adjusted relative position, respectively.

6. In a device of the character described, a supporting frame, a dump bucket open at one side, a loading chute rigid with said bucket and opening into the bucket at said open side, said bucket and chute being mounted on the frame for pivotal movement about a horizontal axis and the chute being normally supported in horizontal position to receive its load, means for inclining the chute to cause it to deliver its load to the bucket through said open side; said bucket having a discharge mouth which opens downwardly when the chute is so inclined, downwardly opening gates for the discharge mouth, and releasable means adapted to hold said gates closed.

7. In a device of the character described, a supporting frame, a dump bucket open at one side, a loading chute rigid with said bucket and opening into the bucket at said open side, said bucket and chute being mounted on the frame for pivotal movement about a horizontal axis and the chute being normally supported in horizontal position to receive its load, means for inclining the chute to cause it to deliver its load to the bucket through said open side, means on the frame and bucket adapted to coact to limit the degree of inclination of the chute; said bucket having a discharge mouth which opens downwardly when the chute is so inclined, downwardly opening gates for the discharge mouth, and releasable means adapted to hold said gates closed.

8. In a device of the character described, a supporting frame, a dump bucket open at one side, a loading chute rigid with said bucket and opening into the bucket at said open side, a screen bottom in said chute, said bucket and chute being mounted on the

frame for pivotal movement about a horizontal axis and the chute being normally supported in horizontal position to receive its load, means for inclining the chute to cause it to deliver its load to the bucket through said open side; said bucket having a discharge mouth which opens downwardly when the chute is so inclined, a pair of gates for the discharge mouth and hingedly connected to the bucket, means for selectively moving said gates hingedly and holding them against movement hingedly; said means including a pair of links pivotally connected to one another at one end and pivotally connected at their other ends, one to each of said gates, a sheave connected to the links at a point spaced from their connection with the gates, a second sheave associated with the first sheave, said sheaves being capable of relative bodily movement, a cable trained over the sheaves, and means for operating said cable to move the sheaves bodily toward and away from each other and hold them at positions to which they have been moved thereby to vary the angular disposition of the links and hold them in adjusted relative position, respectively.

9. In a device of the character described, a supporting frame, a dump bucket open at one side, a loading chute rigid with said bucket and opening into the bucket at said open side, a screen bottom in said chute, said bucket and chute being mounted on the

- 1 a supporting frame, a dump bucket open at one side, a loading chute rigid with said bucket and opening into the bucket at said open side, said bucket and chute being mounted on the frame for pivotal movement about a horizontal axis and the chute being normally supported in horizontal position to receive its load, means for inclining the chute to cause it to deliver its load to the bucket through said open side, said bucket having a discharge mouth which opens downwardly when the chute is so inclined, a pair of closure gates hingedly connected to the bucket adjacent the mouth, and releasable means adapted to hold said gates closed; said means including a pair of links pivotally connected to one another at their upper ends and pivotally connected at their lower ends, one at each of said gates, a travelling sheave at the pivotal connection between links, a sheave, stationarily mounted, except for rotation, on the bucket, a cable trained over said sheaves, and means for operating said cable to vary the distance between said sheaves and hold them at adjusted position thereby to vary the angular disposition of the links and hold them in adjusted relative angular position, respectively.
- 5 8. In a device of the character described, a supporting frame, a dump bucket open at one side, a loading chute rigid with said bucket and opening into the bucket at said open side, said bucket and chute being mounted on the frame for pivotal movement about a horizontal axis and the chute being normally supported in horizontal position to receive its load, means for inclining the chute to cause it to deliver its load to the bucket through said open side; said bucket having a discharge mouth which opens downwardly when the chute is so inclined, gates for the discharge mouth, and releasable means adapted to hold said gates closed.
- 10 9. In a device of the character described, a supporting frame, a dump bucket open at one side, a loading chute rigid with said bucket and opening into the bucket at said open side, said bucket and chute being mounted on the frame for pivotal movement about a horizontal axis and the chute being normally supported in horizontal position to receive its load, means for inclining the chute to cause it to deliver its load to the bucket through said open side, means on the frame and bucket adapted to coact to limit the degree of inclination of the chute; said bucket having a discharge mouth which opens downwardly when the chute is so inclined, gates for the discharge mouth, and releasable means adapted to hold said gates closed.
- 15 10. In a device of the character described, a supporting frame, a dump bucket open at one side, a loading chute rigid with said bucket and opening into the bucket at said open side, said bucket and chute being mounted on the frame for pivotal movement about a horizontal axis and the chute being normally supported in horizontal position to receive its load, means for inclining the chute to cause it to deliver its load to the bucket through said open side; said bucket having a discharge mouth which opens downwardly when the chute is so inclined, gates for the discharge mouth, and releasable means adapted to hold said gates closed.
- 20 11. In a device of the character described, a supporting frame, a dump bucket open at one side, a loading chute rigid with said bucket and opening into the bucket at said open side, said bucket and chute being mounted on the frame for pivotal movement about a horizontal axis and the chute being normally supported in horizontal position to receive its load, means for inclining the chute to cause it to deliver its load to the bucket through said open side; said bucket having a discharge mouth which opens downwardly when the chute is so inclined, a pair of gates for the discharge mouth and hingedly connected to the bucket, means for selectively moving said gates hingedly and holding them against movement hingedly; said means including a pair of links pivotally connected to one another at one end and pivotally connected at their other ends, one to each of said gates, and means applied to the links at their pivotal connection with one another and adapted both to move said links relatively to vary their angularity and to hold said links from relative angular movement.
